Application May 23, 1935, Serial No. 23,112
In Germany May 24, 1934

14 Claims. (Cl. 179—16)

The present invention concerns a circuit arrangement for repeating impulses in long distance communication systems, particularly telephone systems, having devices for the correction of the impulses. In such systems difficulties arise in that on the one hand, long impulses occur on account of distortion, for example during selection, which should be shortened to the proper length, and on the other hand, long impulses occur which are produced intentionally, for example for release in the case of alternating current selection, which should be passed on unshortened.

To satisfy both conditions at the same time is difficult and only possible by detailed switching and then the disadvantage frequently arises that not only the selecting impulses but also the releasing impulses are passed on corrected so that on release an undesirable switching process is brought about, such as the connection of ringing current to the desired subscriber. The present invention obviates this disadvantage in that the impulse repeater relay only causes the repeating of each received impulse on the termination of the latter, and is so influenced through auxiliary relays that the length of the repeated impulses is always brought to the necessary value for producing proper operation.

The attached Figures 1 and 2 illustrate embodiments of the invention, while Fig. 3 is a diagram. Only those switching means necessary for understanding the invention are shown.

In Fig. 1, L₁ represents the incoming end of a junction line with leads *a* and *b*, while L₂ represents the outgoing end of this line. The incoming impulses are received by the alternating current receiving relay J₁. The relay J₁ is alternately energized and deenergized by the impulses. On the energizing of relay J₁, the following circuit for relay M₁ is closed: earth, contact 4₁, winding of relay M₁, battery, earth. Relay M₁ closes the following circuit for relay V₁: earth, contact 1₁ m₁, windings I and II of relay V₁, battery, earth. Relay V₁ energizes and short circuits its winding I through its contact 1₉ v₁. It thus acts as a slow acting relay and holds during an impulse train. Relay V₁ by the opening of its two contacts 2₁ v₁ and 3₁ v₁ disconnects during the transmission of the impulses, the incoming line from the outgoing line. At the end of the impulse, relay J₁ releases and consequently relay M₁ releases. Since relay V₁ holds during the impulse train, the following circuit is formed for relay G₁ on the release of relay M₁: earth,

contacts 1₂ m₁, 1₃ v₁, 1₅ t₁, winding of relay G₁, battery, earth. Relay G₁ maintains relay V₁ energized over contact 1₆ g₁, after the release of relay M₁. Relay G₁ locks itself in the following circuit, independently of relay T₁: earth, contacts 1₇ g₁, 1₆ h₁, winding of relay G₁, battery, earth. Relay G₁ also closes the following circuit for the relay T₁: earth, contacts 1₇ g₁, 1₈ g₁, winding of relay T₁, battery, earth. As long as relay M₁ is deenergized relay T₁ holds independently of relay G₁ in the following circuit: earth, contacts 1₂ m₁, 1₃ v₁, 1₄ t₁, winding of relay T₁, battery, earth. After relays G₁ and T₁ have energized earth is applied to the outgoing *a*-lead over the contacts 2₀ t₁ and 2₀ g₁ shown in dotted lines and the impulse is thus repeated. After relays G₁ and T₁ have energized the following circuit is completed for relay H₁: earth, contacts 8₁, 9₁, winding I of relay H₁, battery, earth. Relay H₁ energizes and takes over the repetition of the impulse over the *a*-lead by applying earth by means of contact 1₁ h₁. The holding circuit for relay G₁ is broken after relay H₁ energizes, by the opening of contact 1₆ h₁. Relay G₁ releases. The repeating of the impulse on the *a*-lead would, however, be brought to an end on account of the opening of contact 2₁ g₁ if the further repeating of the impulse had not been taken over by the relay H₁, as already mentioned. After the release of relay G₁, relay H₁ also deenergizes, on account of the opening of contact 9₁ g₁. Relay H₁ makes a delayed release, because the winding II of relay H₁ is short-circuited through contact 5₁ m₁ and hence the relay acts as a slow acting relay. On the next impulse relay J₁ again energizes. Relay J₁ effects the energizing of relay M₁. Relay M₁ by opening its contact 1₂ m₁ effects the release of relay T₁ and again closes, through a contact 1₁ m₁, the circuit for the slow acting relay V₁. After the termination of this impulse relays J₁ and M₁ again release. The interaction between relays G₁, T₁ and H₁ already described, again sets in and effects the repeating of the impulse.

The manner of working of the correcting device is made more easily understood by reference to Fig. 3 in which various incoming impulses, some of them extremely distorted, are shown diagrammatically. The scale of the diagram is chosen so that 1 mm. on the abscissa represents 2 milliseconds.

The diagram I shows the case in which the make period of the incoming impulse occupies 60 milliseconds (ms.) and the break period 40 ms. 55

The relay J_1 is therefore energized for 60 ms. and deenergized for 40 ms. Since relay M_1 may take 10 ms. in which to operate, this energizes after 10 ms. Relay V_1 (which remains 5 operated during the whole impulse train) may take the same time to operate, 10 ms. after the release of relay M_1 relay G_1 energizes similarly, relay T_1 energizes 10 ms. after relay G_1 , and after a further 10 ms. relay H_1 energizes. Relay G_1 releases 10 ms. after the energizing of relay H_1 . Relay T_1 releases 10 ms. after the energizing of relay M_1 or relay G_1 . The corrected impulse extended through relay H_1 is illustrated on the abscissa H_1 by continuous lines. It can 10 be seen from this figure that the relay H_1 whose winding I is deenergized after the release of relay G_1 , is energized considerably more than 10 ms. after this, and in this case it follows that after the relays J_1 and M_1 have again been energized, through the second incoming impulse at the beginning of the first energizing of relay H_1 , the winding II of relay H_1 , previously short circuited over contact $5m_1$, is short circuited over the circuit: earth, contact $4j_1$, $6m_1$, winding 15 II of relay H_1 , contact $1h_1$, earth, and is thereby made slow to release. The time for release thus produced occupies 30 ms. Since the repeating of the impulse begins after the energizing of relays G_1 and T_1 , over contacts $20t_1$ and $21g_1$, the total duration of the repeated impulse is 50 ms. of which 10 ms. is effected by relays G_1 and T_1 (shown by dotted lines on the H_1 axis) and 40 ms. by relay H_1 .

Diagram 2 illustrates a number of impulses in which the current make lasts for 50 ms. and the current break lasts for 30 ms. As is apparent from the diagram the method of operation of the arrangement according to the invention does not differ in this case from that of diagram 1. The total duration of the repeated impulse again occupies 50 ms.

Diagram 3 is drawn up on the assumption that the impulse make lasts for 20 ms. and the impulse break lasts 40 ms. It follows from this diagram that the short circuit for relay H_1 , after its first energization through the contacts $4j_1$ and $6m_1$ already closed by the second impulse, is again interrupted after the energizing of relay H_1 on account of the opening of contact $4j_1$. Relay M_1 holds in the following circuit, in this case: earth, contact $1h_1$, winding II of relay H_1 , contact $4m_1$, winding of relay M_1 , battery, earth. In this circuit the winding II of relay H_1 , which forms a differential winding with respect to winding I of this relay, is energized. This effects the immediate undelayed release of relay H_1 . The impulse repeated through the contact $1h_1$ correspondingly lasts 30 ms. To this there is still to be added 10 ms. through the closing of contacts $21g_1$ and $20t_1$, as shown in dotted lines on the H_1 axis. Relay M_1 released 10 ms. after the release of relay H_1 . As is indicated in the diagram, the duration of the second impulse extended over contact $1h_1$, only amounts to 20 ms. It is, however, increased by 10 ms. by relays G_1 and T_1 to a total of 30 ms.

Diagram 4 shows quite an arbitrary distortion of each of the incoming impulses of an impulse train unlikely to occur in practice. Thus the first current make lasts for 40 ms., the first current break for 20 ms., the second current make 50 ms., the second current break 30 ms., the third current make 30 ms., the third current break 40 ms., the fourth current make 20 ms., the fourth current break 50 ms., and the fifth current make

60 ms. As can be seen immediately from the diagram of the repeated impulses are elastically adapted to the incoming impulses. The duration of a repeated impulse never falls below 30 ms.

It should be mentioned that the connection 5 to earth over the connection and contacts $20t_1$ and $21g_1$ indicated by dotted lines, can be dispensed with if the pause, which is determined by the time of release of relay M_1 plus the sum of the time taken to energize by relays G_1 , T_1 and H_1 , is not too long. This is the case, for example, when the release times do not as assumed in the diagram amount to 10 ms., but for example only actually amount to 5 ms. In this case relay H_1 by itself always extends impulses of sufficient 15 length.

This is the case assumed in Figure 2 which shows essentially the same arrangement as Fig. 1. In addition Figure 2 exhibits a special feature in that the precaution is taken that besides the correction applied to each individual impulse the first impulse of each impulse train experiences an additional lengthening. This happens for the following reason: since in the case of traffic over several junction lines with impulse correcting devices in each individual stage, particularly if the correcting devices only correct in an arbitrary manner and are not self-adjusting, on account of the difference in loss between the first and second impulse of each impulse train, the second impulse approaches nearer to the first one from stage to stage and thereby an absorption of impulses occurs after a few stages, it is necessary to provide correcting devices in individual intermediate stages which prolong the first impulse 25 and thereby, of course, cause a greater pause between impulses 1 and 2, so that even over a great number of connecting stages it is possible to obtain a passage of impulses which is free from objection.

In Fig. 2 the impulse receiving relay J_2 is alternately energized and deenergized through the incoming impulses from the line L_1 . Relay J_2 by closing its contact $6j_2$ energizes the relay M_2 . By closing its contact $17m_2$ relay M_2 energizes the slow acting relay V_2 . Relay V_2 holds during each impulse, and by the opening of its contact $1v_2$, disconnects the outgoing line L_2 from the incoming line L_1 during each impulse train. In addition relay V_2 , by closing its contact $18v_2$, prepares a circuit for relay G_2 , and by closing its contact $11v_2$, it prepares a circuit for the winding II of relay K_2 . At the end of the first closing of the circuit relays J_2 and M_2 release. Through the release of relay M_2 the relay G_2 is energized in the following circuit: earth, contacts $17m_2$, $18v_2$, $21t_2$, winding of relay G_2 , battery, earth. Relay G_2 energizes and by closing its contact $5g_2$ connects earth to the a -lead. The repeating of the first impulse over the a -lead is thereby initiated. After the operation of relay G_2 and the release of relay M_2 , relay V_2 holds over the contact $15g_2$. Furthermore relay T_2 is energized by relay G_2 in the following circuit: earth, contact $23g_2$, winding of relay T_2 , battery, earth. After relay T_2 has energized the following circuit is closed for relays K_2 and H_2 : earth, contacts $12g_2$, $13t_2$, winding I of relay K_2 , winding I of relay H_2 , battery, earth. Relays H_2 and K_2 operate in this circuit. Relay K holds independently of relays G_2 and T_2 in the following circuit: earth, contacts $10k_2$, $11v_2$, winding II of relay K_2 , battery, earth. Relay K_2 by opening its contact $4k_2$, removes the earth connected to the a -lead, on the operation of relay G_2 , over contact $5g_2$. 75

The repeating of the impulses is, however, taken up at the same instant on account of earth being connected to the *a*-lead through contact 3h2. After the operation of relay H2 the relay G2 releases on account of the opening of contact 19h2. After the release of G2 the circuit for the winding I of relay H2 is broken. If a second impulse has not yet arrived over the line L1, the relay H2 releases slowly on account of the short circuit of the differential winding II, through contact 8m2. An illustration of the method of operation of the correcting device in the case of various kinds of impulse distortions according to Figure 2, by means of diagrams is omitted for it completely corresponds to that of Figure 1. It therefore need only be mentioned that the prolonging of the first impulse by the connection of earth to the *a*-lead immediately relay G2 energizes, cannot be repeated in the case of the other impulses of an impulse train, since after energizing relay K2 holds, during the duration of an impulse train, over winding II. On the termination of the impulse train the holding circuit for winding II of relay K2 is broken on account of the release of relay V2. Relay K2 releases and prepares, by closing its contact 4k2, the immediate repeating of the first impulse of the next impulse train, on the energizing of relay G2, and hence the prolonging of this impulse.

Having described the invention, what is considered to be new and is desired to be protected by Letters Patent will be set forth in the following claims.

What is claimed is:

1. In an impulse correcting repeater arranged to respond to the impulses of a series by transmitting a corrected series of impulses responsive to the receipt of the incoming series of impulses, means for causing the repeating of each impulse of a series only upon the termination of each incoming impulse of a series, and means for causing the repeated impulses to be always of a certain length.

2. In an impulse correcting repeater arranged to receive a series of incoming impulses and to transmit a corrected outgoing impulse for each incoming impulse of a series, and means effective only responsive to the reception of the complete incoming impulse for transmitting an outgoing impulse of a minimum length.

3. In an impulse correcting repeater arranged to receive a series of incoming impulses and responsive thereto to transmit a corrected outgoing series of impulses, an impulse repeating relay, means for operating said repeating relay to repeat an impulse only responsive to the termination of an incoming impulse, and means for governing the length of the repeated impulse.

4. In an impulse correcting repeater arranged to receive a series of incoming impulses and to repeat a corrected series of outgoing impulses, a repeating relay, said repeating relay operated to repeat an outgoing impulse only responsive to the termination of an incoming impulse, and means including said repeating relay for elastically adapting the length of the repeated impulses relative to the incoming impulses.

5. In an impulse correcting repeater arranged to receive a series of incoming impulses and to repeat a corrected series of outgoing impulses, an impulse receiving relay, a repeating relay having its energizing circuit controlled by said impulse receiving relay, means for opening the circuit of said repeating relay independent of said impulse receiving relay, and means controlled by said

impulse receiving relay and depending upon the duration of the received impulses for controlling the time interval taken by said repeating relay to release and terminate the outgoing impulse.

6. In an impulse correcting repeater arranged to receive a series of incoming impulses and transmit a corrected series of outgoing impulses, a repeating relay, an impulse receiving relay, auxiliary relays operated responsive to the de-energization of said impulse receiving relay to effect energization of said repeating relay, and means controlled by said impulse receiving relay and depending upon the length of an incoming impulse for governing the time interval occupied by said repeating relay to release and terminate the length of the outgoing impulse.

7. In an impulse correcting repeater arranged to receive series of impulses and transmit corrected series of impulses, an impulse receiving relay, a repeating relay, said impulse receiving relay when operated closing the operating circuit of said repeating relay, means for opening the operating circuit of said repeating relay to terminate the outgoing impulse independent of said receiving relay, and means for controlling the release time of said repeating relay depending upon the condition of energization of said receiving relay.

8. In an impulse correcting repeater arranged to receive series of impulses and transmit corrected series of impulses, an impulse receiving relay, a repeating relay, said impulse receiving relay when operated closing the operating circuit of said repeating relay, means for opening the operating circuit of said repeating relay to terminate the outgoing impulse independent of said receiving relay, and means for controlling said repeating relay so it operates with a delayed release or a rapid release according to the condition of energization of said impulse receiving relay.

9. In an impulse correcting repeater arranged to receive series of impulses and transmit corrected series of impulses, an impulse receiving relay, a repeating relay having two windings, said impulse receiving relay when operated closing the circuit of one of said windings of said repeating relay to operate the same, means for opening the circuit of said repeating relay winding to terminate the outgoing impulse independent of said receiving relay, and means dependent upon the operating condition of said receiving relay for delaying the release of said repeating relay, said delayed release means comprising a short circuit of the second winding of said repeating relay by said receiving relay.

10. In an impulse correcting repeater arranged to receive series of impulses and transmit corrected series of impulses, an impulse receiving relay, an auxiliary relay operated by said receiving relay, a repeating relay having two windings operated over one winding by joint control of said receiving and said auxiliary relays, means controlled independent of said receiving and auxiliary relays for releasing said repeating relay, and means for short circuiting the second winding of said repeating relay to delay its release independent upon the operating condition of said receiving relay, either after the release of said auxiliary relay or by the reoperation of both said receiving and auxiliary relays.

11. In an impulse correcting repeater arranged to receive series of impulses and transmit corrected series of impulses, an impulse receiving

relay, an auxiliary relay operated by said receiving relay, a repeating relay having two windings operated over one winding by joint control of said receiving and said auxiliary relays, means controlled independent of said receiving and auxiliary relays for releasing said repeating relay, and means controlled by said receiving relay for short circuiting the second winding of said repeating relay to delay its release, said short circuit being removed by the release of said impulse receiving relay and said second winding then being connected in circuit with said auxiliary relay.

12. In an impulse correcting repeater arranged to receive a series of impulses and to transmit a corrected series of outgoing impulses, an impulse receiving relay, an auxiliary relay operated by said receiving relay, a repeating relay having two windings and operated by joint control of said receiving and auxiliary relays over one of said windings, means for releasing said repeating relay independent of said receiving and auxiliary relays, means controlled by said receiving relay for short circuiting said second winding of said repeating relay to delay its release in case the auxiliary relay is released, said second winding

arranged differentially with respect to the first winding, and means for energizing said second winding in series with said auxiliary winding in case said auxiliary relay is operated to effect the rapid release of said repeating relay. 5

13. In an impulse correcting repeater arranged to receive a series of impulses and to transmit a corrected series of outgoing impulses, means for effecting the repeating of a corrected outgoing impulse of a series responsive to the termination 10 of an incoming impulse of a series, and means for prolonging the first one of an outgoing series of impulses.

14. In an impulse correcting repeater arranged to receive a series of impulses and to transmit a 15 corrected series of outgoing impulses, a pair of repeating relays, both of said relays operated responsive to the receipt of the first one of an incoming series of impulses, means for deenergizing one of said relays during the receipt of the 20 remaining impulses of the series, and means controlled by the energized one of said relays for prolonging the length of the first impulse of the outgoing corrected series of impulses.
